MOLD FORM

William E. Mitchell, Altoona, Pa.

Application January 18, 1952, Serial No. 267,044

10 Claims. (Cl. 25—118)

1

This invention relates to a mold form and particularly to a mold form for casting concrete inlets in road construction.

In the construction of modern roadways it is customary to drain the road surface by means of so-called inlets which are arranged at the edge of the travelled surface and have at least a portion of the opening extending onto the travelled surface and having it closed by means of a grating over which vehicles or other traffic may pass. It is customary to form these inlets by providing suitable mold structures and casting cementitious or concrete aggregates between the mold form structures so that a complete unitary concrete structure is formed. Heretofore these mold structures have been constructed from wooden members and have been extremely expensive both in materials and time. The recent increase in cost of timber material has greatly augmented the difficulty in connection with wooden forms. Also, the scarcity of skilled labor for building such forms has greatly retarded road construction.

The present invention provides an inlet mold structure constructed substantially of standard steel forms particularly standard steel channel forms. The channel forms being connected in edge to edge relation by means of bolts or other suitable fasteners secured to the adjacent flanges and the outer walls being arranged in successive vertical and horizontal position so that the walls automatically reenforce each other.

It is an object of this invention to provide a steel mold for concrete inlets.

It is a further object of this invention to provide a steel mold which is separable for removing from the finished cast.

It is a further object of this invention to provide a steel mold which is self-supporting.

It is a further object of this invention to provide a steel mold constructed of standard steel shape.

It is a further object of this invention to provide a steel mold in which the inner mold member may be supported on the outer mold member.

It is a further object of this invention to provide an inlet mold in which the inner form may be readily adjusted with respect to the outer form.

It is a further object of this invention to provide an improved inlet form having means for molding in the seat for receiving the necessary traffic carrying grating.

It is a further object of this invention to provide a steel mold which can be readily adjusted to various sizes.

It is a further object of this invention to provide a steel mold which may be readily demounted from the finished inlet structure.

A further object of this invention is to pro-

2

vide frame means for providing chamfered edges on the tops of the casting.

It is a further object of this invention to provide a mold which can be assembled readily with unskilled labor.

Other objects and many of the attendant advantages of this invention will be apparent from the following detailed description taken in conjunction with the accompanying drawings in

10 which:

Figure 1 is a rear elevation of the exterior form of an inlet mold according to this invention;

Figure 2 is a front elevation of the exterior form of an inlet mold as shown in Figure 1;

15 Figure 3 is a side elevation of the exterior forms of Figures 1 and 2;

Figure 4 is a top plane view of the mold;

Figure 5 is a front elevation of the interior mold form of an inlet mold;

20 Figure 6 is a rear elevation of the interior mold form;

Figure 7 is a side elevation of the interior mold form;

Figure 8 is a top plan view of the interior mold form;

25 Figure 9 is a cross section through the inlet mold taken substantially on the plane indicated by the line 9—9 of Figure 3;

Figure 10 is a vertical section taken substantially on the plane indicated by the line 10—10 of Figure 1;

Figure 11 is a vertical section taken substantially on the plane indicated by the line 11—11 of Figure 3;

30 Figure 12 is an enlarged fragmentary section taken substantially on the plane indicated by the line 12—12 of Figure 4 showing the methods of adjusting and securing the cross beam supporting the inner mold on the outer mold;

Figure 13 is an enlarged fragmentary section taken substantially on the plane indicated by the line 13—13 of Figure 4 showing the method of mounting the chamfer producing frame on the mold forms;

Figure 14 is a top plan view of the finished inlet with a portion of the grill broken away;

Figure 15 is a vertical section through the inlet taken substantially on the plane indicated by the line 15—15 of Figure 14; and

50 Figure 16 is an enlarged fragmentary vertical section taken substantially on the plane indicated by the line 16—16 of Figure 14 showing the steel seat embodied in a concrete seat in the finished inlet wall.

In the exemplary embodiment of the invention 55 the mold consists of an inner form 10 and an outer form 12, the outer form consisting of a rear wall 14, a front wall 16 and side walls 18 and 20. The rear wall 14 is constructed of a plu-

rality of channel plates 30 arranged in edge to edge relation and having the edge flanges 32 of each of the channel plates 20 connected to each other by means of suitable separable fasteners such as bolts 34. The flanges of the channel members 30 being assembled in edge to edge relation to provide the necessary height for the back wall 14.

The side walls 18 and 20 are constructed of channel members 36 arranged in vertical formation and having the edges 38 arranged in edge to edge relation and connected by means of bolts 40. Various widths of channels 36 may be assembled to provide any desired width of the walls 18 and 20.

The rearmost flanges 42 of the walls 18 and 20 are connected to the webs 44 of the channels 36 providing the rear wall so that the flange 42 of the side walls rigidly reinforces the back wall 14 so that it is in rigid self-sustaining relation. Preferably the connection of the flanges to the webs is made by means of suitable separable fasteners such as bolts 46.

The front 16 through which the drain connection or pipe 50 extends is modified slightly from the construction of the rear wall 14 and has a plurality of channel members 52 arranged in edge to edge relation and being connected together by means of bolts or other suitable fasteners 54. The channels 52 are connected to the front flanges of the side walls 18 and 20 and therefore rigidify the structure the same as the channels 30 rigidify the back section. A portion of the front wall is constructed of a pair of plates 56 and 58 which extend into abutting relation and has an end of each plate attached to the flanges 60 which form the front flanges of the walls 18 and 20. An angle member 62 has a flange edge thereof attached to the bottom flange of the channel members 52 and the plates 56 and 58 overlap the lower edge of the web of the flange and are secured thereto by means of bolts 64. In this structure the angle members provide the rigidity necessary for maintaining the form against the weight of the concrete when it is first cast therein while the plate provides the necessary structure in which the pipe 50 may be mounted. The plates 56 and 58 are provided with arcuate surfaces 70 and 72 which provide a substantially circular opening at the abutting ends of the plates 56 and 58, adjusting plates 74 and 76 are provided with arcuate faces 78 and 80 which are substantially in conformity to the arcuate surfaces 70 and 72. The plates 74 and 76 are connected to the plates 56 and 58 respectively by means of bolts 82 and 84 which extend through horizontal slots 86 in the plate 56 and slot 88 in the plate 58 so that the plates 74 and 76 are readily adjustable to and from each other to control the size of the opening therebetween. Preferably the plate 74 is provided with vertical slots 90 and plate 76 is provided with vertical slots 92 for engagement respectively with the bolts 82 and 84 so that the plates 74 and 76 may be vertically adjusted as well as laterally adjusted on the plates 56 and 58 to conform to the size and shape of any pipe 50 which may be introduced through the opening. Horizontally extending plate 94 extends across the abutting edges of the plates 56 and 58 and is made vertically adjustable by means of the vertical slots 96 and 98 so that the plate 94 may be adjusted upwardly or downwardly over the edge of the opening between the plate to readily abut against any pipe 50 which may be inserted through the open-

ing therein. A similar plate 100 is connected below the pipe 50 and is connected by means of bolts 102 and 104 to the plates 56 and 58 and is likewise vertically adjustable and may if desired be provided with an arcuate set-out portion 106. It will thus be seen that the front wall in addition to being rigid is provided with an adjustable opening into which a pipe may be inserted and the mold form accurately adjusted thereto so that the cementitious material will have little or no leakage space therearound. It is usually desirable to have an extension or footing in front of the front wall and under the pipe 50 and for this purpose a short channel extension 108 is secured to the front flange 60 of the side walls 18 and 20 and horizontal channel members 110 and 112 are secured to the extension by means of suitable bolts 114 and 116. Channel members 110 and 112 extend in alignment and terminate in spaced relation to each other so that a space 118 is provided between the ends of the channels 110 and 112 and bar member 120 is connected across this space to rigidify the structure and provide a mold form for retaining cementitious material thereagainst.

The rear wall 14 is a noticeably amount higher than the front wall 16 so that a rear wall may be cast on the inlet which is higher than the front wall. Likewise the channel members adjacent the rear wall 14 are of greater length and extend upwardly further than the remaining channel members of the sides 18 and 20.

The inner mold 130 is constructed as having side walls 130 and 132 constructed of vertically arranged channel members arranged edge to edge and bolted together into a solid formation. By means of bolts 136 the front wall members 138 and the rear wall member 140 are constructed of angle plates which will presently be described.

The vertically extending angle member 134 of the walls 130 and 132 may be selected at any desired number and width to produce the necessary dimensions of the side walls 130 and 132. Each of the corners of the inner mold is provided with an angulated channel 142 which is constructed by taking the channel member and bending it through the longitudinal axis thereof to provide a corner member or angle having inturned flanges at each of the edges thereof. The angles 140 are angulated channels having flanges 144 and 146 with the angle channel flange 144 connected to the flanges 148 of the channels 134. The front wall 138 is constructed of a flange plate which is conveniently constructed by taking a plurality of angle members having flanges and webs and cutting out portions 152, 154 and 156 and arranging them in rectangular formation with the corners welded as shown in Figure 11 the interior of the plate being filled in by means of a rectangular plate welded in position. Flanges of the plate 138 are detachably connected to the angulated corner pieces so that the structure is substantially solid in formation. The rear plate is likewise constructed of angle members 162, 164 and 166 welded together in rectangular formation and filled in with the rectangular plate 168 an upstanding hood 170 detachably connected to the rear plate 140 and the entire rear wall secured to the sides by attachment to the angulated corners.

A supporting beam 176 is connected to the top flange of the front wall 138 and is arranged substantially in the plane of the exterior surface of the wall so as to form a substantial continuation of the wall. The beam 176 extends outward-

ly past the outer walls 18 and 20 and is received in U-shaped slots 178 and 180 in the walls 18 and 20. The U-shaped slots 178 and 180 are provided with U-shaped angle members 182 and 184 an adjusting screw 186 is mounted in the bottom of the U-shaped members 178 and 180 and is adjustable upwardly therethrough and is locked in adjusted position by means of lock nuts 188 and 190. The screws 186 contact the bottom of the beams 176 so that the beams 176 may be vertically adjusted within the slots 178 and 180 so that the inner mold structure may be relatively adjusted with respect to the side members of the outer frame structure.

Preferably the beam structures 176 is composed of a channel member 194 having the open side thereof closed by a plate 196 welded or otherwise secured across the flanges of the channel. The side flanges of the U-shaped members 184 and 182 are provided with a series of openings 198 in which fasteners 200 such as a bolt may be inserted so that the beam 176 is rigidly connected to the end walls 18 and 20 to rigidify the structure thereof. Since the weight of the concrete might cause the vertically extending channel members to be bowed outwardly the beam is rigidly connected to both of the side walls 18 and 20 so that they cannot bow outwardly under the weight of the concrete therein.

It will thus be seen that the beam 176 serves the double purpose of reenforcing the end walls of the outer frame and supporting the inner frame on the outer form.

In a similar manner a beam 202 is supported on U-shaped brackets 204 and 206 and supports the rear wall of an inner form in adjusted position with respect to the outer form. The beam 202 together with hood 170 provides an expanded rear wall on the inner form which provides a space or mold form higher than the front portion of the form so that a high rear wall may be cast therein. The hood portion 170 extends inwardly over the inner mold form so that it presents an underside structure to provide a lift 210 on the finished inlet form. In the construction of an inlet it is necessary to provide a seat for the grating which covers that portion of the opening over which the traffic passes. This is accomplished by means of a pair of seat forms 220 and 222 each of which are composed of box-like forms having an outer channel member 224 and 226. The outer channel forms being closed by means of plates 228 and 230 secured across the open ends of the flanges of the channel preferably by welding. Each of the closure plates have box-like seat holes and is provided with a plurality of longitudinally extending slots 232 and 234 in which is slidably connected fastening members such as bolts 240. The side walls 132 and 130 are likewise provided with vertically extending slots 242 in which the bolts 40 are vertical slidable and may be secured by means of nuts 246 to adjustably secure the box-like forms in any desired position on the exterior surface of the inner mold side walls.

Angular metal seats 250 may be detachably secured to the lower outside corner of the seat molds so that when the finished structure is cast the seats will have reenforcing iron or metal corner members. Preferably the metal seats 250 are temporarily secured to the box-like forms 220 and 222 by suitable flexible fasteners such as wire 252.

As hereinbefore set out the rear wall 14 is higher than the front wall 16 while the adjacent

channel members of the side walls 18 and 20 are of increased height and together with the hood 170 and the beam 202 enclose a substantially rectangular top portion 260 and in which the top or extended portion forming the curb of the inlet will be fashioned. Since this top portion of the inlet will be subject to contact with traffic it is desirable to chamfer or round off the exposed corners so that they will not be broken or chipper away by contact with traffic. The space 262 is provided with a chamfering mold in a form of a rectangular frame 270 having upstanding brackets 272 and 274 while the top channels of the rear wall are provided with openings 276 for adjustable connection with a bolt 278 so that the frame 270 may be adjustable with respect to the back wall. Likewise, the beams 202 is provided with openings 280 for cooperation with the bolts 282 for securing the frame 270 on the cross beam 202. The frame 270 is substantially rectangular in formation and is provided with angle shaped side members 283 which extend into the cementitious material to provide chamfered edges 284. Reinforcing bars 286 extend across the sides of the frame 270 to rigidify the same.

In operation of the device the frame is set into a desired opening and the bottom of the frame may be contoured as desired to provide any desired configuration of the bottom of the inlet. The pipe or sewer 50 is connected into the outer mold against the inner mold surface and secured in position by means of the plates 74 and 76 together with the straps 94 and 100. The inner mold form is adjusted to the proper height by means of the adjusting screws 186 and the entire form rigidified by connecting the cross beams 176 and 202 to the respective U-shaped members on the end walls of the outer frame so that the outer frames will properly support the weight of the concrete material therein. The rear wall of the inlet is provided by means of the upstanding rear wall portions of the molds and the entire mold structure is filled with concrete material between the inner and outer forms to provide the inlet 300 having seats at the opposite ends thereof for seating the grill 304, the top of the back wall or curbing 262 being provided with an inturned edge 210 to overlie a portion of the inlet and having chamfered edges 284.

The form is particularly versatile as the size may be readily changed by substituting channel members of different widths for minor changes or adding or removing channels for larger changes of dimensions.

It frequently happens in different jurisdictions that the standard specification calls for cement walls of different thickness. This is of course readily provided in certain of the walls by exchanging one or more channel sections. However, certain transverse members would necessarily be of different length. This is compensated for by constructing the transverse members of sufficient length to meet maximum specifications and providing a plurality of rows of fastening openings corresponding to other standard specifications.

While for purposes of exemplification a particular embodiment of the invention has been shown and described according to the best present understanding thereof, it will be apparent to those skilled in the art that many changes and modifications can be made therein without departing from the true spirit of the invention.

Having described the invention, what is claimed as new is:

1. A form for a concrete inlet comprising an outer form including a rear wall composed of channel members detachably secured in edge to edge relation and disposed in horizontal position, a pair of side walls composed of channel members detachably secured in edge to edge relation and disposed in vertical position, said horizontal members being detachably secured to the edges of the corner vertical channels of said side walls, a front wall composed of a plurality of channel members detachably connected in edge to edge relation, a pair of plates detachably secured to the edge of one of said channel members, said channel members and said plates being detachably secured to the edge of the front corner channels of said side walls, an inner form including a pair of side walls composed of vertically disposed channel members detachably secured in edge to edge relation, corner members composed of angulated channel members, front and back plates detachably secured to said corner channels, supporting beams detachably secured to said front and rear plates substantially in the planes of the upper edges of said plates, means for detachably securing said beams to said side walls of said outer form whereby bulging of said outer form walls is substantially prevented.

2. A form for casting inlets comprising walls formed of channel members detachably secured in edge to edge relation, the channel members of two opposed walls being disposed vertically, the channels of the cross walls being disposed horizontally, the webs of the horizontal channels being detachably secured to the flanges of the corner channel of the walls with vertically disposed channels, an inner form including two opposed walls formed of vertically disposed channel members secured in edge to edge relation, angulated channel members detachably secured at each corner of said inner form, flanged plates detachably connected to opposed angulated corners to provide two opposed plate walls, a support beam rigidly secured to the top of each of said support plate walls, said beams being mounted on and secured to said outer walls formed of vertically disposed channels, said support beams being vertically adjustable with respect to said outer walls.

3. A mold form comprising a back wall composed of horizontally disposed channel members in edge to edge relation, a pair of side walls composed of vertically disposed channel members detachably secured in edge to edge relation, the rear flanges of said side walls contacting the webs of the channels composing the rear wall, separable fasteners detachably securing said rear flanges to the webs of the channels of said rear wall, a front wall including a plurality of horizontally disposed channel members in edge to edge relation, separable fasteners securing the front flanges of said side walls to the webs of said plurality of channel members, a pair of plate members disposed in abutting relation, the top edges of said plates being detachably secured to the bottom flange of said plurality of channel members, the outside ends of said plates being detachably secured to the front flanges of said side walls, the abutting edges of said plate members being contoured to provide a substantially circular opening therebetween, said plates terminating in spaced relation to the bottom of said side walls, extension members secured adjacent the bottom edge of said side walls, chan-

nel members detachably secured to said extension members, in parallel relation to said front wall, said channel members terminating in aligned spaced relation, means detachably connecting said channel member in substantially rigid relation.

4. An inner mold form including a pair of side walls composed of vertically disposed channel members in edge to edge relation, the abutting flanges being detachably connected together, angulated corner channels secured to said side walls, a front wall including a flanged plate, the side flanges of said plate being detachably connected to the flanges of said angulated corner channels a substantially horizontally disposed beam, the upper flange of said plate being detachably secured to the bottom of said beam, a back wall including a flanged plate, a hood having a flanged edge, the flange of said hood being detachably secured to the top flange of said back flanged plate, the top of said hood extending inwardly of said form and terminating in substantially extending relation, a second beam substantially parallel to said first mentioned beam, said hood being detachably connected to said second beam, said beams extending laterally beyond said side walls.

5. A mold form comprising a back wall composed of horizontally disposed channel members in edge to edge relation, a pair of side walls composed of vertically disposed channel members detachably secured in edge to edge relation, the rear flanges of said side walls contacting the webs of the channels composing the rear wall, the channels of said rear wall being detachably secured to said rear flanges, a front wall including a plurality of horizontally disposed channel members in edge to edge relation, separable fasteners securing the front flanges of said side walls to the webs of said plurality of channel members, a pair of pipe receiving plate members disposed in abutting relation, said plates being detachably secured to the bottom flange of said plurality of channel members and to the front flanges of said side walls, said plates terminating in spaced relation to the bottom of said side walls, extension members secured at the bottom edge of said side walls, a channel member detachably secured to each of said extension members, said channel members terminating in aligned spaced relation, means detachably connecting said channel member in substantially rigid relation, an inner mold form including a pair of side walls composed of vertically disposed channel members in edge to edge relation, the abutting flanges being detachably connected together, angulated corner channels secured to said side walls, a front wall including a flanged plate, the side flanges of said plate being detachably connected to the flanges of said angulated corner channels, a substantially horizontally disposed beam, the upper flange of said plate being detachably secured to the bottom of said beam, a back wall including a flanged plate, a hood having a flanged edge, the flange of said hood being detachably secured to the top flange of said back flanged plate, the top of said hood extending inwardly of said form and terminating in substantially extending relation, a second beam substantially parallel to said first mentioned beam, said hood being detachably connected to said second beam, said beams extending laterally beyond said side walls.

6. A mold form comprising a back wall composed of horizontally disposed channel members

in edge to edge relation, a pair of side walls composed of vertically disposed channel members detachably secured in edge to edge relation, the rear flanges of said side walls contacting the webs of the channels composing the rear wall, said rear flanges being detachably secured to the channels of said rear wall, a front wall including a plurality of horizontally disposed channel members in edge to edge relation, separable fasteners securing the front flanges of said side walls to the webs of said plurality of channel members, a pair of pipe receiving plate members disposed in abutting relation, said plates being detachably secured to the bottom flange of said plurality of channel members and to the front flanges of said side walls, said plates terminating in spaced relation to the bottom of said side walls, extension members secured at the bottom edge of said side walls, channel members detachably secured to said extension member, said channel members terminating in aligned spaced relation, means detachably connecting said channel member in substantially rigid relation, an inner mold form including a pair of side walls composed of vertically disposed channel members detachably secured in edge to edge relation, angulated corner channels secured to said side walls, a front wall including a flange plate detachably connected to said angulated corner channels, a substantially horizontally disposed beam, said plate being detachably secured to the bottom of said beam, a back wall including a flanged plate, a hood having a flanged edge, said hood being detachably secured to the top of said back flanged plate, the top of said hood extending inwardly of said form and terminating in substantially extending relation, a second beam substantially parallel to said first mentioned beam, said hood being detachably connected to said second beam, said beams extending laterally beyond said side walls, U-shaped slots in said outer side walls, said beams extending through said slots, said beams being detachably secured in said slots.

7. A mold form comprising a back wall composed of horizontally disposed channel members in edge to edge relation, a pair of side walls composed of vertically disposed channel members detachably secured in edge to edge relation, the rear flanges of said side walls contacting the webs of the channels composing the rear wall, said rear flanges being detachably secured to the channels of said rear wall, a front wall including a plurality of horizontally disposed channel members in edge to edge relation, separable fasteners securing the front flanges of said side walls to the webs of said plurality of channel members, a pair of pipe receiving plate members disposed in abutting relation, said plates being detachably secured to the bottom flange of said plurality of channel members and to the front flanges of said side walls, said plates terminating in spaced relation to the bottom of said side walls, forwardly extending extension members secured on said side walls adjacent the bottom thereof, channel members detachably secured to said extension members, said channel members terminating in aligned spaced relation, means detachably connecting said channel members in substantially rigid relation, an inner mold form including a pair of side walls composed of vertically disposed channel members detachably secured in edge to edge relation, angulated corner channels secured to said side walls, a front wall including a flange plate detachably connected to said angulated corner channels, a substantially horizontally disposed beam, the upper

flange of said plate being detachably secured to the bottom of said beam, a back wall including a flanged plate, a hood, a second beam substantially parallel to said first mentioned beam, said hood being detachably connected to said back wall and to said second beam, said beams extending laterally beyond said side walls, U-shaped slots in said outer side walls, said beams extending through said slots, said beams being detachably secured in said slots, adjusting means for vertically adjusting said beams in said slots.

8. A mold form comprising outer side walls composed substantially of channel members detachably secured together, inner side walls composed substantially of channel members detachably secured in edge to edge relation, front and back plate members secured between said inner side walls, horizontally extending beam members secured at the top of said front and back plate members, vertical U-shaped slots in said outer side walls, said beams being received in said slots, flanges about said slots, a vertically extending threaded member secured in the bottom of said U-shaped flanges, said threaded member adjustably supporting said beams in said slots, means detachably securing said beams to the sides of said U-shaped slots.

9. A mold form including inner and outer mold members, back walls on said inner and outer mold members, said back walls extending above the front walls, that portion of the outer side walls adjacent the outer back wall being of greater height than the front walls, a beam secured to said inner back wall and being connected to said outer side walls, a frame slidably received in the space enclosed by said back walls and said side portions, means for adjustably securing said frame in said space said frame being constructed of tapered members whereby a casting in said space is provided with chamfered corners.

10. A mold comprising an outer form, an inner form, supporting means secured to said inner and outer forms for supporting said inner form in said outer form, said inner form being spaced from said outer form, and seat molds secured to said inner form, each of said seat molds including a box-like member, including a channel member, a closure plate secured across the flanges of said channel member, a pair of longitudinally extending slots in said closure plate, bolts slidably mounted in said slots, vertically arranged slots in said inner form, said bolts being slidably received in said vertical slots and means for securing said bolts to fasten said seat forms in adjusted position.

WILLIAM E. MITCHELL.
